UNITED STATES PATENT OFFICE.

ARTHUR HARRY ROPER PULMAN, OF LONDON, ENGLAND, ASSIGNOR OF TWO-THIRDS
TO OLIVER PRESCOTT MACFARLANE, OF LONDON, ENGLAND.

INTERNAL-COMBUSTION ENGINE.

1,201,098.

Specification of Letters Patent. Patented Oct. 10, 1916.

Application filed April 12, 1915. Serial No. 20,904.

To all whom it may concern:

Be it known that I, ARTHUR HARRY ROPER PULMAN, a subject of the King of Great Britain, residing at 30 Victoria 5 House, South Lambeth road, S. W., in the county of London, England, have invented certain new and useful Improvements in or Relating to Internal-Combustion Engines, of which the following is a specification.

10 This invention has reference to internal-combustion engines, and relates more particularly to engines of the kind or class in which the working pressure is exerted between the pistons or plungers moving in opposite directions in the working cylinder, and operating a single crank.

15 A feature of the invention consists in simplifying the general construction of the engine and providing an arrangement of 20 parts which more nearly resembles the standard construction of ordinary vertical or marine steam-engines, by causing the two pistons to drive one and the same cross-head which in turn actuates the crank.

25 A further feature of the invention consists in arranging that the rear or auxiliary piston can be adjusted relatively to the front piston (or vice versa) in a very simple and convenient manner, so that the clearance between the two pistons can be varied to enable the engine to work either with oil or 30 gas as may be desired. This adjustment can be effected without necessarily having to vary the length of stroke of the auxiliary piston, or to take the engine to pieces and 35 both pistons may be made adjustable if desired.

40 Another feature consists in providing on the working cylinder, a pump cylinder the piston of which may be carried by one of the working pistons, for instance the front or main piston. According to one example, the air-pump piston is connected to one end 45 of a rocking lever or beam, the opposite end of which is connected by a side rod or rods to a sliding-piece constituting the cross-head for the rod of the first mentioned or front piston, such cross-head driving the 50 crank by a single main connecting-rod in the ordinary way, under the joint impulse of the two oppositely-moving pistons. By coupling the main connecting rod centrally to the sliding-piece or cross-head and midway between the front piston rod and the 55 side rod, a balanced action is obtained, and

twisting strains on the cross-head are avoided. The relative adjustment of the rear or auxiliary piston may be effected by making the rod which connects it to the rocking lever, adjustable in length, or the said rocking lever may have an adjustable pivot or fulcrum to enable the throw to be varied as required within certain limits.

60 A further feature of the invention consists in arranging the sprayer or oil or spirit jet, so that it feeds into the cylinder at the place where the two pistons come nearest together.

65 In order that the invention, which also comprises other features hereinafter referred to, may be clearly understood and readily carried into effect reference will now be had to the accompanying diagrammatic drawings in which:—

70 Figure 1 illustrates in vertical section, 75 one example of an engine constructed in accordance with the invention, and in which the rear piston is adjustable. Fig. 2 is a fragmentary view of a modification in which the front piston is adjustable.

75 a is the working cylinder, which is fitted with the two oppositely-moving pistons b and c, of which b is that referred to as the auxiliary piston, whereas c is regarded as the main piston on account of being nearer 80 to the crank and having a more direct connection therewith.

85 d is the pump cylinder or air compressor, which is formed on the said working cylinder, and has its piston e carried by the piston rod c¹ of the lower or main piston c. The area of the pump piston may be one and a half times that of the working piston, more or less.

90 f is the rocking lever or beam, to one end 95 of which the upper piston is coupled by its connecting rod g, and which is supported by a bracket f¹.

100 h is the side-rod which passes through a hole or gap in the frame or standard k, and serves to connect the other end of the lever f to a yoke or cross-beam i which extends from a suitably-guided sliding-piece i¹. This sliding piece i¹ may conveniently 105 be guided in the portion j of the frame or standard k, somewhat after the manner in which an ordinary cross-head is guided. The side-rod h may be connected with the said cross-beam by a pin l.

110 k¹ is a standard or support at the oppo-

site side of the working cylinder to the standard k .

n is the main connecting rod which is coupled to the yoke or cross-beam i by a pin and fork arrangement at n^1 or otherwise, and thus serves to actuate the crank p by the joint impulse of the two pistons. That is to say the lower piston acts through its piston rod c^1 , while the upper piston acts through the lever f and side rod h on the two opposite ends of the sliding piece or cross-head, and a balanced action is obtained owing to the connection of n being midway between that of h and c^1 , as shown.

The rear piston may be made adjustable (as above indicated) to vary the clearance or space for containing the explosive mixture. In the example shown, by forming the rod g in two parts which are united by an adjustable connection such as a screw-collar g^1 engaging the oppositely threaded ends of the said two parts, the clearance between the pistons can be varied as desired, to suit different fuels for instance. This enables the engine to be adjusted to work economically with either oil or gas as may be convenient without necessarily varying the length of stroke, and without having to remove any of the parts, or to more or less dismount the engine. The side-rod (or rods in case two are used) where it is fitted to the lever f , may have a ball-and-socket or other flexible joint to permit of a little play if necessary, to avoid strain. Thus with a double-piston arrangement, it is possible to use only a single main connecting-rod and crank for both the oppositely-moving pistons, and if three or more cylinders be arranged side by side, there need only be one crank to each cylinder, just as in a steam engine. It will be seen that the top or rear piston can be readily removed by disconnecting the rocking lever or beam, as no cover is required at that end of the cylinder. Two or more cylinders may be arranged in connection with each crank, either opposite each other, or at any other desired angles, and these may be so set that an explosion stroke in one corresponds to a compression stroke in the opposite one.

The pump chamber d forms, as it were, an enlarged end to the working cylinder, there being a shoulder or off-set part at the junction. It serves for providing the scavenging air, and also a certain amount of air to mix with the fuel to form the charge.

For the sake of simplicity only one of each set of ports is shown, that for the exhaust being shown at m , while that for the scavenging air is shown at m^1 . The said scavenging air is led from the pump d to the port or ports m^1 by any suitable pipe or passage, such as d^1 , connected with the delivery opening d^2 of the pump. The air inlet to the pump is indicated at d^3 .

In the modification shown in Fig. 2, the air-compressor d on the lower end of the cylinder is omitted, the cylinder being left open at the bottom, just as it is open at the top (see Fig. 1). The lower or main piston c is also made adjustable, by threading its rod c^1 at the part where it passes through the left-hand end of the cross-head i (Fig. 1) and providing it with two adjusting nuts c^2 , so that it can be raised or lowered relatively to the cross-head. Thus when an alteration of clearance is required, the top and bottom pistons may each be adjusted by an equal amount.

With a cylinder open at both ends as in Fig. 2, the employment of liquid supply pipes for cooling the pistons is considerably facilitated. In such a case, of course, a separate air pump or compressor is used, operated in any convenient manner.

One or both of the adjacent surfaces of the two pistons are or may be, provided with intermediate recesses or cut-away portions q forming a kind of mouth, channel, or chamber into which the charge from the sprayer r is injected, this mouth or chamber lying for instance half in one piston and half in the other. This mouth may lead into a spherical cavity or chamber s also formed half in one piston and half in the other, and one piston may have a raised rim or edge t to fit in a corresponding rabbet or groove t^1 in the other, to prevent the compressed charge reaching the cold walls of the cylinder. In some cases however the intermediate recess may be entirely of wedge-shape, having a rectangular cross-section and a tapering longitudinal section, with the end of the taper near the middle of the piston. By the use of either a spherical chamber or a wedge-shaped or other recess of this kind, the working fluid can more readily enter and act between the pistons.

Obviously the invention may be modified in various ways in carrying the same into practice without departing from the general nature thereof.

I claim:—

1. In an internal-combustion engine, the combination of two oppositely-moving pistons, a single cross-head operated by the joint action of said two pistons, and moving in the same direction as one of the pistons, and a crank driven from such cross-head and common to the two pistons, substantially as described.

2. In an internal-combustion engine, the combination of two oppositely moving pistons, a cross-head, guiding means for such cross-head parallel with the pistons, a crank, a connecting rod extending from the middle of said cross-head, a piston-rod and side-rod connected to opposite ends of said cross-head to secure a balanced action, and a rocking lever for transmitting motion from one

of the pistons to the said side-rod, substantially as described.

3. In an internal-combustion engine, the combination of two oppositely moving pistons, a single cross-head, a rocking lever and side rod connecting the rear piston with the cross-head and reversing the motion due to said rear piston, a piston rod connecting the main piston therewith, and a single connect-

ing rod and crank arrangement driven from 10 said cross-head, substantially as described.

In testimony whereof I affix my signature in presence of two witnesses.

ARTHUR HARRY ROPER PULMAN.
